UNITED STATES PATENT OFFICE.

FRANK WERNER AND JOHN HINK, OF GRAND RAPIDS, MICHIGAN.

SAFE

Application filed November 14, 1927. Serial No. 233,066.

This invention relates to a safe and is more concerned with an individual safe which may be embedded in concrete or similar masonry and kept on the premises, that is, in the wall 5 of a dwelling house or other structure where the one who owns the safe lives. The safe of our invention may be used to house valuables such as ordinarily are kept in safety deposit vaults.

10 The construction of safe which we have devised is one practically impossible to open without possession of the key which operates the lock used in conjunction with the front end closure of the safe. The construction 15 which we have devised and which has proved practical and completely satisfactory is described in the following description and shown in the accompanying drawing, in which,

20 Fig. 1 is a partial vertical section and side elevation, the safe itself being shown in side elevation and the installation and outer covering door therefor in vertical section.

25 Fig. 2 is a fragmentary enlarged vertical section through the front end of the safe and the closure therefor.

30 Fig. 3 is a fragmentary horizontal section through the lock used in conjunction with the safe, the operating key for the lock being shown in association therewith.

35 Fig. 4 is a fragmentary front end view of the safe compartment, the front closure being removed and showing the position of the tumblers of the lock, and

40 Fig. 5 is a fragmentary horizontal section through the front end and closure of the safe, looking downwardly upon the lugs on the safe and the cooperating engaging members on the closure which detachably connect therewith.

Like reference characters refer to like parts in the different figures of the drawing.

45 The safe proper comprises a hollow compartment 1 open at its front end, designed to be embedded in masonry like the concrete illustrated at 2, and having an enlargement 3 at its front end. Around the front portion of the compartment it is somewhat thickened and provided with an annular integral ring

50 4, back of enlargement 3. At the inner side of the compartment 1 and at least two spaced apart points are integral lugs 5 which are disposed at an angle, as shown, to the front open end of the compartment. Within the

compartment, at its front end, it is formed 55 with an annular shoulder 6 where the enlargement 3 joins therewith.

At the front end of the compartment 1 a series of spaced apart cylindrical openings 7 are bored inwardly for a distance into the 60 thickened ring portion 4 in which cylindrical locking tumblers 8 are slidably received, the same being normally projected outwardly 65 some distance beyond the front end of the compartment by springs 9 seated in the openings 7. These springs are attached at their smaller ends to the tumblers 8 and at their larger ends fit in the openings 7 frictionally so that the tumblers will not fall out of the 70 openings 7. It will be observed, referring 75 to Fig. 4, that the openings 7 are not the same distance from the longitudinal central axis of the compartment 1 but that each opening from one end opening to the other stands out a little farther from such axis. This is 80 a feature of the invention, the purpose of which will later appear, and which is very necessary for the practical operation of the same.

The front end of the compartment 1 may 85 be closed by a door 10 which has engaging hooked members 11 at its rear side to engage with the lugs 5 on the inner sides of the compartment 1. The door also has a handle 12 at its outer side. It will also be observed 90 that the door is machined at its inner side to have a projecting portion 13 which fits against the shoulder 6, previously described as made at the outer end of the cylinder 1. By turning the door 10 about the axis of the compartment the members 11 may be made to engage back of the lugs 5 and the door drawn 95 snugly to closed position.

At proper places near one edge of the door 10 a plurality of openings 14 are bored from 100 the inner side outwardly nearly to the outer side of the said door and so positioned that the same will come into exact conjunction with the various openings 7 in the cylinder 1 when the door has been turned to its tightly 105 closed position.

The openings 14 do not extend entirely through the door 10 but from their ends other short openings 15 of smaller diameter do extend to the outer face of the door. Within 110 each of the openings 14 a headed pin 16 is mounted which passes through a fixed guide ring 17 between which and the head of the

pin and around each pin a light coil compression spring 18 is placed. The springs normally move the headed pins 16 so that the heads of the pins come against the shoulders 5 between the openings 14 and 15.

It is evident that when the door is applied to the compartment 1 within the front enlargement 3 and turned to bring the door to tightly closed position, the openings 14 in 10 the door will come into direct alignment with the various openings 7 in the cylinder 1. When this occurs the locking tumblers 8 will be projected outwardly by the springs 9 to enter the openings 14, whereupon the door 10 15 cannot be turned in either direction and is locked against turning movement, and therefore, securely locked against detachment due to the fact that the members 11 cannot disengage from the lugs 5 until turned sufficiently 20 ly to have their ends pass completely by each other. It will be further noted that if all of the openings 7 and the openings 14 to correspond therewith were in an arc of the same radius from the center of the compartment, 25 when the first opening 14 came to the first opening 7 a tumbler 8 would enter said first opening 14 and lock the device so that it could not be further moved, one tumbler only being engaged and the door not up to its tightly 30 closed position. It is for this reason that the various openings 7 and the openings 14 corresponding thereto are located at different distances from the axis of the compartment and of the door.

Unlocking the door is attained by means 35 of a key which is illustrated at the right in Fig. 1 and also in Fig. 3. The key comprises a flat plate 19, from one edge of which a plurality of pins 20 of different lengths extend. 40 There are the same number of pins as there are locking tumblers and the diameter of the pins is such that they pass freely through the holes 15 to engage the heads of the pins 16. The pins 16 also are of different lengths and 45 are of such lengths that the combined length of any pin 20 and the pin 16 which it engages is always equal to the combined length of any other pin 20 and the pin 16 which it engages. Therefore, when the key is applied by inserting the pins 20 through the openings 15 all 50 of the pins 16 are moved whereby their inner ends come to the dividing line between the rear side of the door and the front end of the safe 1. This moves the locking tumblers 8 back, as shown in Fig. 3, and all of them are 55 fully disengaged from the openings 14, the door is unlocked and may be turned to disengage from the cylinder 1.

In practice, as before stated, the safe may

be embedded in concrete or other masonry and preferably in the face of the masonry a recess is made which is lined with sheet metal lining 21 having a flanged opening therein extending into the front end of the enlargement 3 on compartment 1. An additional door 22 of fire proof material closes the recess and lies flush with the outer side of the masonry wall, protecting the contents of the safe from fire.

The construction described provides a safe which is substantially secure against unauthorized entrance, and one which can be built in a wall or in a block of masonry as desired. The advantages of the construction are obvious.

The invention is defined in the appended claims and is to be considered comprehensive of all forms of structure coming within their scope.

We claim:

1. In a device of the class described, a receptacle having a circular opening, a circular closure for said opening, interengaging means on said receptacle and said closure for holding the closure over said opening, said means being engaged or disengaged by rotation of the closure, a plurality of locking tumblers carried by the receptacle near the periphery of said opening, a plurality of openings in the closure near its periphery to receive the tumblers, said tumblers and openings being so located that all of said tumblers are simultaneously received in the openings on turning movement of the closure about its center to a predetermined position.

2. In a device of the class described, a receptacle having a circular opening, a circular closure for said opening, interengaging means on said receptacle and said closure for holding the closure over said opening, said means being engaged or disengaged by rotation of the closure, a plurality of locking tumblers carried by the receptacle near the periphery of said opening, a plurality of openings in the closure near its periphery to receive the tumblers, said tumblers and openings being so located that all of said tumblers are simultaneously received in the openings on turning movement of the closure about its center to a predetermined position and each of said respective tumblers and openings being located at different distances from the respective centers of the opening and closure.

In testimony whereof we affix our signatures.

FRANK WERNER.
JOHN HINK.
